UNITED STATES PATENT OFFICE.

EMIL JAGENBERG, OF DUSSELDORF, GERMANY.

PAPER-STRIP FOLDING AND PRESSING DEVICE FOR BOX-MACHINES.

1,058,061.

Specification of Letters Patent.

Patented Apr. 8, 1913.

Application filed December 31, 1912. Serial No. 739,523.

To all whom it may concern:

Be it known that I, EMIL JAGENBERG, a citizen of the Empire of Germany, residing at Dusseldorf, in the Empire of Germany, have invented a new and useful Paper-Strip Folding and Pressing Device for Box-Machines, of which the following is a specification.

In machines for making boxes of the class described in the U. S. Patents No. 996,856 of July 4, 1911, and No. 1,016,266 of February 6, 1912, both granted to Richard Höglfeldt, boxes are made from rectangular blanks cut out squarely in the four corners, to form four sides that are scored at the junction with the bottom. The machine first turns up the sides, covers the same with a strip of paper, that projects over both ends of the box, turns in such ends by means of two folding devices, and presses the turned in ends against the bottom and also against the inner side of the box. Such box machines present the disadvantage, that the turning-up of the sides, the winding of the paper strip around the turned-up sides and the folding of the projecting edges of the paper strip can be effected only consecutively, which results in a considerable loss of time. Moreover the first plunger requires to be fed forward step by step.

My invention relates to improvements in such box machines, whereby the manufacture of the boxes is accelerated and the machine is rendered capable of making exactly shaped boxes of all sizes without air bubbles in the paper cover.

The chief improvement consists in providing the slide for shifting the box blank from one extreme position to the other extreme position and vice versa with two folding devices and a single cam disk for operating the two folding devices, also with box pressing devices.

Other improvements will be hereinafter set forth and pointed out in the claims.

I will now proceed to describe my invention with reference to the accompanying drawings, in which— Figure 1 is an elevation of a box machine embodying the improvements according to my invention, Fig. 2 is a plan view of the same, Fig. 3 is a vertical cross section through the line A—B in Fig. 2, seen in the direction of the arrows, the slide occupying one extreme position as shown in

Fig. 2 and parts being omitted, Fig. 4 is similar to Fig. 3, the slide occupying the other extreme position, parts on the right of the vertical central line of the slide being omitted to show a cam disk, Fig. 5 is a vertical section through the line C—D in Fig. 3, seen in the direction of the arrows, an upper part being shown in elevation, Fig. 6 is the elevation of an annular supporting plate with one pressing device disposed thereon, Fig. 7 is the elevation of a square supporting plate with one slide guided thereon, Fig. 7^a is a side view of the same, Fig. 8 is the elevation of a cam disk for operating the folders, Fig. 8^a is a horizontal central section through this cam disk, Fig. 9 is a perspective view of a box blank and most of a paper strip wound around the same, Fig. 10 is a vertical longitudinal section on an enlarged scale through the first plunger, a piston located therein, a box blank on the first plunger with a paper strip wound around the sides of the box, a spring-pressed holder and parts carrying the holder, Fig. 11 is a horizontal central section through the box blank with the paper strip, the piston, two movable spring-pressed holders and two lateral pressing devices with parts of folders, Fig. 12 is a vertical section through the box blank with the paper strip, the upper and lower pressing devices and parts of folders appertaining thereto, and Fig. 13 is a vertical section through the box blank with the paper strip, the second plunger, an abutment and the upper and lower pressing devices, Figs. 10, 11, 12 and 13 illustrating four stages of the process of folding and pressing the paper strip.

Similar characters of reference refer to similar parts throughout the several views.

In Figs. 1 and 2 the machine frame proper is shown as consisting of a base 45, three lower standards 46, 47, 48, a table 49 and two upper standards 50, 51. In the two upper standards 50, 51 a driving shaft 52 is mounted to turn, which has loose on it a driving pulley 53 and fast a gear wheel 54. By means of a handle 55 and a clutch 56 the gear wheel 54 can be at will coupled with the driving pulley 53 and disconnected therefrom. Parallel to the driving shaft 52 another shaft 57 is mounted to turn in the two upper standards 50, 51 and has fast on it a long drum 58, a short drum 59 and two gear wheels 60, 61. The left gear wheel 60

meshes with the above mentioned gear wheel 54. A third shaft 62 parallel to the two shafts 52, 57 is mounted in the two upper standards 50, 51 to longitudinally move. 5 On the shaft 62 a hollow shaft 63 is mounted to longitudinally move through the right upper standard 51. A tube 65 is mounted to turn in the right upper standard 51 on the hollow shaft 63 and is prevented 10 from endwise motion. This tube 65 has fast on it a frame 66 and a gear wheel 64 which meshes with the above mentioned gear wheel 61. The long drum 58 has two cam grooves 67 and 68, in which two rollers 69, 70 on two 15 levers 71, 72 respectively engage. The upper ends of the levers 71, 72 are slotted and in these slots engage two pins 73, 74 on lugs of two shackles 75, 76 fastened respectively on the two concentric shafts 62, 63. The 20 solid shaft 62 is at the outer end rigidly connected with a piston 43 (Fig. 10) and the hollow shaft 63 may be at the outer end rigidly connected with a first plunger 41. As is clearly shown at Fig. 10, the first 25 plunger 41 has a recess, which is normally filled up by the piston 43, so that the outer faces of the plunger 41 and the piston 43 are made to normally flush. In a bracket 77 (Fig. 2) on the right upper standard 30 51 a rod 78 is mounted to longitudinally move and carries a second plunger 44 (Fig. 13). The rod 78 is pivotally and adjustably connected by means of a rod 79 with a lever 80, which rocks at 81 (Fig. 2) on the left upper standard 50. The lever 80 carries a roller 82, which engages in a cam groove 83 provided in the short drum 59. It will be now seen, that the second plunger 35 44 is periodically reciprocated from the short drum 59 and that the long drum 58 serves for periodically shifting the first plunger 41 and the piston 43 independently of one another.

The parts hitherto described form parts 45 of the box machine proper, which latter in its appearance certainly departs from the machines shown and described in the said U. S. Patents Nos. 996,856 and 1,016,266 but 50 described in the said patents as far as regards the forming of the box from a blank on the first plunger 41 and the winding of a gummed paper strip 42 around the sides of the box. I shall not further describe here 55 the box machine proper, as it forms no part of the present invention.

A shaft 84 parallel to 52 is mounted to turn in the two outer lower standards 46, 48 and has fast on it a drum 85, a gear wheel 60 86 and two juxtaposed cam disks 87, 88. As the gear wheel 86 meshes with the above-mentioned gear wheel 54, it will be seen, that the shaft 84 is rotated from the driving pulley 53. The drum 85 has a cam groove 89, 65 in which a roller 90 on an arm 91 engages.

The arm 91 is fastened on a shaft 92 mounted to rock in suitable bearings (not shown) on the underside of the table 49.

According to my invention the slide distinct from the box machine proper and disposed on the right end of the table 49 (Figs. 1 and 2) is improved upon, and the whole paper-strip folding and pressing device is constructed as follows: A support 93 (Figs. 1, 2, 3) is fastened on the table 49 and comprises two parallel horizontal guides 16, 16 (Fig. 5), in which a slide 15 is mounted to reciprocate. The slide 15 has an arm 94 (Fig. 2), which is pivotally connected by means of a rod 14 with the upper arm 95 of a bent lever 95, 96 rocking on a pin 97 fastened in the table 49. The lower arm 96 of this lever carries a roller 98 (Fig. 2), which engages in a cam groove of the cam disk 87. The cam groove of this cam disk is so shaped as to periodically shift by means of the parts 98, 96, 95, 14 the slide 15 from one extreme position shown at Fig. 3 opposite to the first plunger 41 to the other extreme position shown at Fig. 4 opposite to the second plunger 44 and vice versa. On the outer end of the above mentioned shaft 92 is fastened an arm 99, which is pivotally connected by means of a rod 23 passing through an aperture 100 of the support 93 with the lower arm 22^a of a two-armed lever 22, 22^a rocking at 101. The upper arm 22 carries a pin 29, which will be referred to later. The slide 15 is made in one with a cylindrical boss 102, 103, in which a spindle 24 is mounted to longitudinally move, while it is prevented from turning in the boss 102, 103 in a manner to be hereinafter explained. The spindle 24 has fastened on it two parallel disks 26, 26 and is adapted to travel 105 with the slide 15 through a horizontal slot 25 provided in the support 93, whereby the slide is permitted to freely move. The spindle 24 is rigidly connected with an abutment 21 (Fig. 13). A rail 27 parallel with the two guides 16, 16 is fastened by means of two studs 140, 140 (Fig. 2) on the support 93 and is made to normally engage between the two disks 26, 26. The rail 27 has at the right end in Fig. 3 a cut 28 for permitting the two disks 26, 26 with the spindle 24 and the abutment 21 to longitudinally move after the pin 29 has engaged between the two disks 26, 26 for the extreme position of the slide 15 shown at Fig. 4. Of course 110 when during the stroke of the slide 15 from right to left in Fig. 3 the two disks 26, 26 move off the pin 29, they will be no longer shifted by the pin but engage the rail 27 and will be thereby prevented from endwise 115 motion, while the two-armed lever 22, 22^a is permitted to freely rock under the action of the cam groove 89 in the drum 85. Then the abutment 21 will simply lean against the outer end of the boss 102, 103. 120 125 130

On the cylindrical boss 102, 103 of the slide 15 (Fig. 5) a toothed segment 11 (Fig. 4) is mounted to turn, which meshes with a horizontal rack 10. The rack 10 is longitudinally movable and is guided by two rollers 104, 104 disposed on the support 93 and engaging in the two slots 105 of the rack. The rack 10 has on the inner side two lugs 10^a, 10^a, between which engages the rounded head of an upper arm 12 fastened on a shaft 106 rocking in the support 93. At the outer end of the shaft 106 is fastened an arm 12^a (Figs. 1, 2, 3, 5) carrying a roller 12^b, which engages in a cam groove 107 (Fig. 3) of the cam disk 88 for producing certain effects to be explained later.

On the boss 102, 103 is fastened a square supporting plate 5 (Figs. 7 and 7^a), which has four radial slots 108, 108 and two holes 109, 109. On both sides of each slot 108 is disposed a pair of guides 110, 110 on the plate 5 for a slide 6, which is made in one with an arm 4 at right angles to it (Fig. 5). A cam disk 9 of the shape shown at Figs. 8, 8^a is fastened on the toothed segment 11 and is thus made to move with the latter on the inner side of the square plate 5. Each slide 6 is provided with a pin 111 (Fig. 7) carrying a roller 7, which engages through the slot 108 of the plate 5 into one of the four cam grooves 8, 8, 8^a, 8^a of the cam disk 9. It will be understood, that when the toothed segment 11 with the cam disk 9 is turned in one direction, say that of the arrow 112 in Fig. 8, the four slides 6 will be radially moved outward by the rollers 7, 7 in certain steps for the upper and lower slides and in other steps for the two lateral slides in accordance with the shape of the cam grooves 8, 8, 8^a, 8^a. When the toothed segment 11 is turned in the opposite direction, of course the four slides 6, 6 will be moved inward.

An annular supporting plate 2 of the shape shown at Fig. 6 is rigidly connected by means of four studs 115 (Fig. 5) with the square supporting plate 5, the studs engaging in holes 116, 116 of the plate 2 and in holes 117, 117 of the plate 5. The plate 2 has eight triangular inner projections 113, 113, into which eight pins 114, 114 are screwed. Two of these pins 114, 114 engage in slots 118, 118 in two lugs 119, 119 of a plate 120 (Fig. 6) and serve for radially guiding this plate 120. There are in all four movable plates 120, 120 disposed on the plate 2, as is shown in Fig. 3. In accordance with the size and shape of the box blank 40 (Fig. 9) formed and surrounded with a gummed paper strip 42 in the present example a long plate 121 is rigidly connected with the upper and lower plate 120 (Fig. 6). The plate 121 in turn is rigidly connected by means of two studs 122, 122 with a cheek 1, which has the same size as one

long wall of the box 40 and is lined with felt 134 (Figs. 10, 13, 15). To each lateral plate 120, on the contrary, a block 123 (Fig. 3) is attached, the end face of which has the same size as one short wall of the box and is also lined with felt 135 (Fig. 11). Each plate 120 is pressed outward by means of two helical springs 124, 124 (Fig. 6), so that the inner ends of the slots 118, 118 are in contact with the pins 114, 114. Into each lug 119 two adjusting screws 19, 19 (Figs. 3, 4) are screwed, which are surrounded with helical springs 20, 20 and serve for guiding a small plate 18 provided with a central lug. Into two of the holes 125, 125 of the plate 2 (Fig. 6) are screwed two pins 126, 126, on which two two-armed pressing levers 17, 17 are mounted to rock. The ends of the long arms of these levers are made to press on one arm 4 (Figs. 3 and 5) and the ends of the short arms are made to press on the lugs of the two plates 18, 18. It will be now evident, that when the arm 4 is in a manner to be hereinafter described forced outward, the arm 4 will turn the long arms of the two levers 17, 17 outward and the short arms inward, so that the cheek 1 is pressed on the long wall of the box 40. The blocks 123, 123 on the two lateral plates 120, 120 serve as cheeks, their inner faces being adapted to press on the two short walls of the box 40. On both sides of the plates 120, 121 and the cheeks 1, 1 two T-shaped folders 3, 3 are disposed (Fig. 5). These folders are made from sheet metal, have suitable apertures, through which the arms 4, 4 pass, and are connected together by means of two plates 127, 128 (Fig. 5) and two screws 129, 129 (Fig. 3). The inner parts of the folders 3, 3 slightly exceed the cheeks 1, 1 in length. The parts 1, 122, 122, 121, 120, 119, 119, 114, 114, 19, 19, 18, 18, 20, 20, 17, 17 (Fig. 6) form an upper or lower pressing device.

The two lateral pressing devices are similarly constructed and differ from the upper and lower pressing devices in that the blocks 123 replace the parts 121, 122, 122, 1. The folders 3^a, 3^a on each lateral pressing device differ from those on the upper and lower pressing devices in that their inner parts are shorter and only slightly exceed the blocks 123 in length. The lateral folders 3^a, 3^a are quite flat (Fig. 11) and their inner edges are slightly rounded. The corners of the upper and lower folders 3, 3, however are slightly bent outward, as is clearly shown in Figs. 10, 12 and 13. In consequence of this the corners of the lateral folders 3^a, 3^a are permitted to periodically engage under the corners of the upper and lower folders 3, 3, as is clearly shown in Fig. 4.

The cylindrical boss 102, 103 of the slide 15 (Fig. 5) is provided with two recesses 130 (Fig. 10), which correspond with the above mentioned holes 109, 109 in the square sup-

porting plate 5 (Fig. 7), while the abutment 21 (Fig. 10) has also two corresponding holes 131 of a slightly larger diameter. A hollow piston 30 is fitted into each hole 109 5 and recess 130 and is adapted to press with its annular end face the bottom of a box 40 against the piston 43. A screw 132 is screwed into the bottom of each recess 130 and a helical spring 133 surrounding the screw 132 serves for normally pressing the piston 30 outward against the head of the screw. When the piston 30 strikes the bottom of the box 40, of course the helical spring 133 will be compressed, as is clearly 10 shown in Fig. 10. It will be seen, that by means of the two pistons 30, 30 the abutment 21 and therewith the spindle 24 is prevented from turning.

The machine operates as follows: After a 20 box 40 (Fig. 9) has been formed from a blank on the first plunger 41 (Fig. 2) and a gummed paper strip 42 has been wound around the walls of the box during one revolution of the first plunger 41, this plunger 25 is by means of its hollow spindle 63 (Fig. 10), the parts 76, 72, 70 and the drum 58 (Fig. 1) moved forward to the right in Figs. 1 and 2, the slide 15 with all parts carried by it occupying the extreme position 30 shown in Figs. 2 and 3. The piston 43 has of course traveled with the first plunger 41, so that their end faces flushing with one another bear on the bottom of the box 40 and consequently both the first plunger 41 and 35 the piston 43 will have so introduced the box blank 40 with the gummed paper strip 42 between the two cheeks 1, 1 and the two blocks 123, 123, that the walls of the box 40 register with them, the four folders 3, 3, 3^a, 3^a having been withdrawn and occupying 40 their outer extreme position as is shown in Figs. 3 and 10. At this moment the two arms 12 and 12^a occupy their extreme position shown in Fig. 3, so that the rack 10 45 occupies its extreme right position shown and the four rollers 7, 7 of the slides 6, 6 are at the ends of the four cam grooves 8, 8, 8^a, 8^a as is shown in Fig. 8. A slight clearance should be left between the paper strip 42 and the felts 134, 134, 135, 135, as is 50 shown in Figs. 10 to 12. The two pistons 30, 30 (Fig. 11) have been pushed back by the piston 43, so that the bottom of the box 40 is securely held between the two pistons 55 30, 30 and the piston 43 and is prevented from shifting, while the first plunger 41 is withdrawn from the box and leaves behind the piston 43 (Fig. 11). At the same time by means of the cam groove 107 (Fig. 3) in 60 the cam disk 88 and by means of the parts 12^b, 12^a (Fig. 2) and 106 (Fig. 5) the arm 12 (Fig. 3) is turned through a small angle to the left and by means of the toothed segment 11 rolling on the rack 10 the cam disk 65 9 (Fig. 8) is turned through a small angle

in the direction of the arrow 112 in Fig. 8, so that the two rollers 7, 7 in the inner cam grooves 8^a 8^a move through a small distance inward, that is into say the middle of the first inner portions of the inner cam grooves 8^a 8^a 70 which are eccentric to the spindle 24 (Fig. 5). In consequence of this the inner edges of the two pairs of lateral folders 3^a, 3^a have struck the paper strip 42 and folded the lateral edges of the paper strip 42 through 75 an angle of say 45° as is shown in Fig. 11. Thereby the box 40 is prevented from shifting during the withdrawal of the piston 43 now taking place, while the two pistons 30, 30 still bear against the bottom of the box 80 40. The arm 12 continues its motion until the two rollers 7, 7 engage in the first nips of the two inner cam grooves 8^a, 8^a, when the arm 12 stops. In consequence of the shape of the inner portions of the cam 85 grooves 8^a, 8^a the lateral folders 3^a 3^a have been moved quite inward and folded the lateral edges of the paper strip 42 through an angle of 90°. As the concentric portions of the outer cam grooves 8, 8 compass a 90 larger angle than the inner eccentric portions of the inner cam grooves 8^a, 8^a, the upper and lower folders 3, 3 still occupy their outer extreme position shown in Figs. 3 and 10 and the upper and lower edges of 95 the paper strip 42 remain unfolded (Fig. 11). Now by means of the parts 98, 96, 95, 14, 94 (Fig. 2) the slide 15 is moved from its extreme position shown in Figs. 2 and 3 to the other extreme position shown in Fig. 100 4, so that the toothed segment 11 rolling on the rack 10 is together with the cam disk 9 (Fig. 8) turned to the right in the direction of the arrow 112 in Fig. 8 and the four rollers 7, 7 have moved through the cam grooves 105 8, 8, 8^a, 8^a quite to the second nips of these grooves. From an examination of Fig. 8 it will be evident, that during the motion of the slide 15 the lateral folders 3^a, 3^a first withdraw and nearly uncover the lateral 110 edges of the paper strip 42, before the upper and lower folders 3, 3 advance inward and fold the upper and lower edges of the paper strip 42 through an angle of 90° (Fig. 12) and then withdraw and nearly uncover the 115 upper and lower edges. At the end of the stroke of the slide 15 by means of the cam groove 89 in the drum 85, the parts 90, 91, 92, 99, 23, 22^a (Fig. 1) the arm 22 is turned to the right in Fig. 5, so that its pin 29 now 120 engaging between the two disks 26, 26 moves the spindle 24 forward and thereby presses by means of the abutment 21 the folded inner edges of the paper strip 42 against the bottom of the box 40, and at the same time 125 by means of the cam groove 83 in the drum 59 (Fig. 1) and by means of the parts 82, 80, 79, 78 (Fig. 2) the second plunger 44 has been moved forward to the right in Fig. 2, so that this plunger engages in the box 40 130

and folds all the outer edges of the paper strip 42 inward. As the second plunger 44 exactly fits the finished box, it will be understood, that the outer edges of the paper strip 42 are now in contact with the inside of the box blank. During the motion of the four rollers 7, 7 through the outer eccentric portions of the cam grooves 8, 8, 8^a 8^a the four arms 4, 4 striking the long arms of the levers 17, 17 and moving them outward cause the short arms to press by means of the lugs on the small plates 18, 18, the lugs 119 on the plates 120, 120 and the upper and lower plates 121 with the studs 122 the cheeks 1, 1 and in a similar manner by means of the lateral plates 120, 120 the blocks 123, 123 against the gummed paper strip 42 on the walls of the box 40, as is shown in Fig. 13. As the finished box is now entirely pressed on the outside and inside, all air-bubbles, if there are any, are squeezed out of the paper strip 42, so that the box is nicely finished. Then the arm 12 in Fig. 3 is turned back to the left, so that the two cheeks 1, 1 and the two blocks 123, 123 withdraw from the walls of the box 40 now left on the second plunger 44, whereupon the latter returns to its initial position shown in Fig. 2. During the return of the second plunger 44 two adjustable bent strippers 136, 136 (Figs. 1, 2) disposed on the bracket 77 strike the finished box and strip it off the second plunger 44, so that the box drops on some chute (not shown) and slides down into some receptacle. Of course during the return of the second plunger 44 also the slide 15 with all parts carried by it is returned to the initial position shown in Fig. 2.

It is evident, that by exchanging the cheeks 1, 1 with the studs 122, 122 and plates 121 of the upper and lower pressing devices, also the blocks 123, 123 of the lateral pressing devices, further the four folders 3, 3, 3^a, 3^a, the abutment 21 and the two plungers 41, 44 for other corresponding parts the machine can be rendered fit for boxes of other sizes.

The paper-strip folding and pressing device for box machines can be varied in many respects without departing from the spirit of my invention.

I claim:

1. In a device of the class described, a support, an abutment guided in said support, a first plunger fitting the inside of the walls of a box blank covered on the walls with a paper strip projecting from the bottom and open top of the box, a piston coaxial with said first plunger and adapted to fit the bottom of the box, means for simultaneously advancing said first plunger and said piston with the blank into the proximity of said abutment, means for withdrawing said first plunger, pairs of parallel fold-
ers radially guided on said support, one

folder of each pair being in the plane of the bottom and the other folder in the plane of the open top of the box, means for so advancing a part of said pairs of folders as to turn a part of the strip edges through an angle while leaving space to said piston, means for withdrawing said piston, means for so advancing a part of said pairs of folders as to turn a part of the strip edges against the bottom and the end face of the box and then withdrawing these folders, means for advancing in a similar manner the other pairs of folders during the withdrawal of the first named folder, a second plunger adapted to fit the finished box, and means for advancing said second plunger into the box so as to turn the upper strip edges against the inside of the box and then withdrawing the second plunger with the box on it.

2. In a device of the class described, a support, an abutment guided in said support, a first plunger fitting the inside of the walls of a box blank covered on the walls with a paper strip projecting from the bottom and open top of the box, a piston coaxial with said first plunger and adapted to fit the bottom of the box, means for simultaneously advancing said first plunger and said piston with the blank into the proximity of said abutment, means for withdrawing said first plunger, slides radially guided on said support, cheeks guided on said slides and adapted to press on the walls of the box, one side of each cheek being in the plane of the bottom and the other side in the plane of the open top of the box, pairs of folders on both sides of said cheeks and rigidly connected with said slides, two-armed levers on said support and adapted to be struck on one arm by said slides when moving outward and to move with the other arm said cheeks inward, means for so moving inward a part of said slides as to cause their folders to turn a part of the strip edges through an angle while leaving space to said piston, means for withdrawing said piston, means for so moving inward a part of said slides as to cause their folders to turn a part of the strip edges against the bottom and the end face of the box and then withdrawing these slides with their folders, means for moving inward in a similar manner the other slides with their folders during the withdrawal of the first named slides, a second plunger adapted to fit the finished box, means for simultaneously advancing during the withdrawal of the other slides said abutment against the bottom and said second plunger into the box so as to turn the upper strip edges against the inside of the box, means for so moving outward said slides as to strike said two-armed levers and to cause them to press said cheeks against the walls of the box, means for so much

moving inward said slides as to withdraw said cheeks, and means for withdrawing said second plunger with the box on it.

3. In a device of the class described, a support having a cylindrical boss with end face, a supporting plate fastened on the end face of said boss, a cam disk turnable on said cylindrical boss and having cam grooves and on the inner side a toothed segment, a rack guided on said support and meshing with said toothed segment, means for intermittently moving said rack, an abutment guided in said boss adapted to press on the bottom of the box, means for periodically moving said abutment, means for supporting and moving into the proximity of said abutment in its normal position a box blank covered on the walls with a paper strip projecting from the bottom and open top of the box, slides radially guided on said supporting plate and having each a roller engaging through a radial slot in said supporting plate in one of the cam grooves in said cam disk, cheeks guided on said slides and adapted to press on the walls of the box, one side of each cheek being in the plane of the bottom and the other side in the plane of the open top of the box, pairs of folders on both sides of said cheeks and rigidly connected with said slides, said folders being adapted to turn the strip edges of the box, and two-armed levers on said supporting plate adapted to be struck on one arm by said slides when moving outward and to move with the other arm said cheeks inward.

4. In a device of the class described, a support, an operating slide guided on said support and having a cylindrical boss with end face, means for periodically reciprocating said operating slide, a supporting plate fastened on the end face of the boss of said operating slide, a cam disk turnable on said cylindrical boss and having cam grooves and on the inner side a toothed segment, a first plunger fitting a box blank covered on the walls with a paper strip projecting from the bottom and open top of the box, an abutment guided in said cylindrical boss and adapted to press on the bottom of the box, means for periodically moving said abutment, means for moving said first plunger with the box blank into the proximity of said abutment in its normal position when said operating slide occupies its one extreme position and withdrawing the first plunger without the box blank, a rack guided on said support and meshing with said toothed segment, means for intermittently moving said rack, slides radially guided on said supporting plate and having each a roller engaging through a radial slot in said supporting plate in one of the cam grooves in said cam disk, cheeks guided on said slides and adapted to press on the walls of the box, one side of each cheek being in the plane of the bottom and the other side in the plane of the open top of the box, pairs of folders on both sides of said cheeks and rigidly connected with said slides, said folders being adapted to turn the strip edges of the box, two-armed levers on said supporting plate adapted to be struck on one arm by said slides when moving outward and to move with the other arm said cheeks inward, a second plunger, and means for moving said second plunger into the finished box when said operating slide occupies its other extreme position and withdrawing the second plunger with the box released.

ALBERT NUFER.

each a roller engaging through a radial slot in said supporting plate in one of the cam grooves in said cam disk, pairs of parallel folders rigidly connected with said slides and adapted to turn the upper and lower strip edges, a second plunger adapted to fit the finished box, and means for moving said second plunger into the box when said operating slide occupies its other extreme position so as to turn the upper strip edges against the inside of the box and then withdrawing the second plunger with the box on it.

5. In a device of the class described, a support, an operating slide guided in said support and having a cylindrical boss with end face, means for periodically reciprocating said operating slide, a supporting plate fastened on the end face of the boss of said operating slide, a cam disk turnable on said cylindrical boss and having cam grooves and on the inner side a toothed segment, a first plunger fitting a box blank covered on the walls with a paper strip projecting from the bottom and open top of the box, an abutment guided in said cylindrical boss and adapted to press on the bottom of the box, means for periodically moving said abutment, means for moving said first plunger with the box blank into the proximity of said abutment in its normal position when said operating slide occupies its one extreme position and withdrawing the first plunger without the box blank, a rack guided on said support and meshing with said toothed segment, means for intermittently moving said rack, slides radially guided on said supporting plate and having each a roller engaging through a radial slot in said supporting plate in one of the cam grooves in said cam disk, cheeks guided on said slides and adapted to press on the walls of the box, one side of each cheek being in the plane of the bottom and the other side in the plane of the open top of the box, pairs of folders on both sides of said cheeks and rigidly connected with said slides, said folders being adapted to turn the strip edges of the box, two-armed levers on said supporting plate adapted to be struck on one arm by said slides when moving outward and to move with the other arm said cheeks inward, a second plunger, and means for moving said second plunger into the finished box when said operating slide occupies its other extreme position and withdrawing the second plunger with the box released.
